BARBECUE GRILLE CART

Blond E. Swadley, Wichita, Kans., assignor to The Coleman Company, Inc., Wichita, Kans., a corporation of Kansas

Filed Sept. 10, 1969, Ser. No. 19,082

Term of patent 14 years

Int. Cl. D12—02

U.S. Cl. D14—3

FIG. 1

FIG. 2

FIG. 3

FIG. 4

FIG. 5

FIG. 1 is a perspective view of a barbecue grille cart embodying my new design, the cart being shown from the side and front;

FIG. 2 is a side elevational view, both sides being identical;

FIG. 3 is a front elevational view;

FIG. 4 is a rear elevational view; and

FIG. 5 is a top plan view.

I claim:

The ornamental design for a barbecue grille cart, as shown.
